UNITED STATES PATENT OFFICE.

GODFREY A. MUELLER, OF POINT PLACE, OHIO, ASSIGNOR TO THE DE VILBISS COMPANY, OF TOLEDO, OHIO, A CORPORATION OF OHIO.

SPRAY GUN.

Application filed April 7, 1927. Serial No. 181,660.

This invention relates to spray-guns of the type commonly known as air-brushes and used to atomize and spray coating materials.

In spray-guns of this character, separate provision is made for feeding both the material to be sprayed and the atomizing air or motive fluid to the spray-head, and both are controlled by independent valves that are commonly actuated to have opening movements by a single operating means. It is desirable in the use of such spray-guns to have the air valve completely opened or opened to a predetermined maximum adjustable extent before the material control valve is opened, so that the initial portion of the material spray may be as finely atomized or subjected to the same volume and pressure of atomizing air as the balance of the spray, thereby preventing the stopping and starting of the spraying operation from being noticed on the work. A control means of the type heretofore used is illustrated in application for U. S. Letters Patent Serial No. 682,700, filed December 29, 1923 now Patent No. 1,613,588 of Jan. 4, 1927.

The object of the invention is the provision of simple and efficient control means for the motive fluid and material valves, which means is operable by a continuous pull thereon or movement thereof in one direction to first open the motive fluid valve to its full extent or to its maximum adjusted position and then to open the material valve to its full extent for which adjusted, so that the desired and resultant advantages may be obtained.

The invention is fully described in the following specification and one embodiment thereof illustrated in the accompanying drawing, in which,—

Figure 1 is a side elevation of a spray-gun embodying the invention with a part in central longitudinal section and with the valves and operating means in normal position. Fig. 2 is a fragmentary side elevation of the spray-gun with the operating means in the position which it assumes when the motive fluid valve is fully opened and the material control valve is closed, and Fig. 3 is a similar view thereof with the operating means in the position which it takes when both valves are fully opened.

Referring to the drawings, 1 designates the body or stock portion of a spray-gun embodying the invention, 2 the spray-head unit carried by the forward end of said body, and 3

the handle projecting down from the rear end thereof. The body 1 is provided with a passage or chamber 4 adapted to have communication (not shown) with a source of fluid pressure supply and also having communication 60 through a passage 5, in the present instance, and other passages (not shown) with the air discharge passage of the spray-head, as well understood in the art. A valve 6 is disposed in the passage 4 and is held normally seated 65 against a restricted portion of the passage by a compression spring 7 at the forward end thereof. A stem 8 projects from the valve rearwardly through a guide portion of the body 1 and into an open space 9 in the body, 70 which space is open at its bottom without the underside of the body.

The fluid discharge passage of the spray-head 2 is controlled by a valve, the stem 10 of which projects rearwardly from the spray-head for reciprocatory movements therein and with its rear end projecting under the body space 9 and bearing against a plunger 11 which normally holds the valve in seated position. This plunger has reciprocatory 80 movements in a socket 12 in the rear end of the body 1 and is normally held in forwardly projected position by a coiled compression spring 13, the forward end of which bears against the plunger while the rear end thereof 85 bears against a stop screw 14 having a shoulder 14^a for coacting with the plunger 11 to limit its rearward movement. Nothing new is claimed for any of the structure so far described, as it is common in spray-guns 90 heretofore used.

The trigger member 15 by which the valves are operated is disposed in advance of the inner end portion of the handle 3 and has its inner end forked and straddling an enlargement 16 on the valve stem 10 and projecting up into the space 9 in position to carry a cross-pin 17 which projects transversely thereof and has its ends projecting into registering longitudinally extending slots 18 provided in the side walls of the body space 9. The trigger is provided on the inner sides of its fork arms with thrust lugs or portions 19 which bear against shoulders 20 on the respective sides of the enlargement 16 so as 100 to exert a rearward pull or thrust on said enlargement and the valve stem 10 when the trigger is drawn rearwardly.

A thrust block 21 is mounted on the pin 17 intermediate the arms of the trigger 15, and 110

upon a forward movement of the upper end portion of the trigger is intended to bear against the rear end of the valve stem 8 to effect an opening of the associated valve 6. 6 A guide arm 22 projects rearwardly from the thrust block 21 through a guide sleeve 23 threaded for axial adjustment in an opening in the rear wall of the space 9. The arm 22 cooperates with its guiding member to support the pin 17 for true horizontal reciprocatory movements when the trigger is moved and carries a stop member 24 on its outer end to coact with the outer end of the sleeve 23 and limit the inward movement of the arm 15 and valve.

It is evident in the use of this control that after a rearward valve opening pull is exerted on the lower end of the trigger 15 the trigger will rock with the portions 19 and 20, serving 20 as a fulcrum therefor, and effect a forward opening movement of the valve 6 to the full extent allowed by the adjusting sleeve 23. This is accomplished by reason of the spring 13 being of greater tension than the spring 25 7, so that the valve stem 10 will be caused to stand still while the valve 6 is being moved to full open position allowed by adjusting sleeve 23. During this movement, the pin 17 moves to the limit of its forward movement 30 in the slots 18 in the body 1 or until the head 24 is stopped by sleeve 23, and when the movement of the pin has stopped either by its engagement with the forward end walls of said slots or by engagement of the stop 24 35 with the rear end of the adjustable guide sleeve 23 through which the arm 22 projects, a continued pull on the trigger 15 will cause it to rock about the pin 17 as a fulcrum and to cause a rearward movement of the valve 40 stem 10 against the tension of the spring 13. In other words, during the opening movement of the air or motive fluid valve 6 the trigger will act about its point of engagement with the valve stem 10 as a fulcrum and when 45 the air valve has been opened to the permissible extent, the pin 17 will then act as a fulcrum for the movement of the trigger which effects the opening movement of the material control valve.

50 Inasmuch as the invention resides entirely in the operating means for the two control valves of the gun and nothing new is claimed for the other parts thereof, as for instance the construction of the spray-head 2 which 55 may be of any suitable form, such parts are not shown or described in detail.

I wish it understood that my invention is not limited to any specific construction, arrangement or form of the parts, as it is 60 capable of numerous modifications and changes without departing from the spirit of the claims.

Having thus described my invention, what I claim as new and desire to secure by Letters 65 Patent is:

1. In a spray-gun, a body, two separate control valves one for the motive agent and the other for the material to be sprayed, said valves having opening movements in opposite directions, separate yielding closing means 70 for the two valves acting with greater force on the material control valve than on the other valve, a sleeve member carried by the body in spaced relation to the motive agent valve for adjustment toward and away from the same, a plunger carried and guided for reciprocatory movements by said sleeve member and having coaction with the motive agent valve to open the same when moved in one direction, said plunger having a stop part for 80 coaction with the sleeve member to limit the valve opening movement of the plunger, a trigger member pivotally carried by said plunger and having a fulcrum point on the material control valve whereby, upon a movement of the trigger in one direction, it will 85 fulcrum on the material control valve and actuate the plunger to open the motive agent control valve, the limit permitted by the adjustment of the sleeve member and then during a continued movement of the trigger to 90 fulcrum on the plunger and impart an opening movement to the material control valve.

2. In a spray-gun, a body having a bottom recess, a motive agent control valve projecting into said recess, a material control valve projecting from the body below said recess, separate means for normally maintaining each valve in closed position and acting with greater force on the material control valve, a 100 sleeve member threaded in the rear wall of said recess for axial adjustment toward and away from the motive agent control valve, a plunger carried for limited reciprocatory movements by said sleeve member and adapted to act against the motive agent valve to 105 open the same, a trigger extending up into said recess and pivoted to said plunger and having a part below the plunger in rearward thrust coaction with the material valve 110 whereby an operating movement of the trigger will first cause it to fulcrum on the material valve and impart predetermined valve opening movement to said plunger and then during a continued movement to fulcrum on 115 the plunger and impart predetermined opening movement to the material valve.

3. In a spray-gun, a body, two separate control valves one for the motive agent and the other for the material to be sprayed carried by the body, said valves having opening movements in opposite directions, separate yielding closing means for the two valves acting with greater force on the material control valve than on the other valve, a reciprocally movable plunger carried by the body in adjacent relation to the motive agent valve and operable when moved in one direction to impart opening movement to the motive agent valve, an adjustable stop for the 120 125 130

plunger to limit the permissible valve opening movements thereof, a trigger member pivotally carried by the plunger and having a fulcrum point adapted to have thrust contact with the material control valve in valve opening direction whereby upon a movement of the trigger in valve opening direction it will fulcrum on the material control valve

and actuate the plunger to open the motive agent control valve to its full permissible extent and will then, during a continuing movement, fulcrum on the plunger and impart an open movement to the material control valve. 10

In testimony whereof I have hereunto signed my name to this specification.

GODFREY A. MUELLER.
